Attorney.

UNITED STATES PATENT OFFICE.

ROBERT E. STURMAN, OF DELANO, MINNESOTA.

FURNACE GRATE.

Original application filed July 18, 1917, Serial No. 175,384. Divided and this application filed January 29, 1919. Serial No. 273,910.

To all whom it may concern:

Be it known that I, ROBERT E. STURMAN, a citizen of the United States, residing at Delano, in the county of Wright and State 5 of Minnesota, have invented a new and useful Improvement in Furnace Grates, of which the following is a specification.

My invention relates to a furnace grate, the primary object of which is to provide 10 a grate that can be easily operated, being of simple construction and having a somewhat conical shape to distribute the fire or fuel in the furnace, or spread it out pyramidal in the furnace in which the grate is placed. This 15 application is a division of my application filed June 18, 1917 bearing Serial No. 175,384.

It is also an object to provide a grate with 20 a series of individual grate bars, which are pivoted at their ends, the inner ends of all of the grate bars being provided with means which connects the segments with operating means so that all of the grate bars of the grate can be rocked simultaneously on their 25 pivot points to shake the grate, or for dumping the same. The grate operating means is of such construction that it can be operated by a lever outside of the furnace in the ordinary manner.

30 A further object of my invention is to provide a grate which is so constructed that the grate bars can be easily removed to be replaced when worn out or for repairs, and of a suitable shape to suit the occasion.

35 In the drawing forming part of the specification:

Figure 1 is a plan view of my grate.

Figure 2 is a section on the line 2—2 of Figure 1.

40 Figures 3 and 4 are detailed portions of the grate construction.

In the drawing A represents my furnace 45 grate which is circular in shape, having a series of triangular shaped grate bars 1 which are formed with lugs 2 on their inner ends, and lugs 3 on their outer ends. The grate bars 1 are pivotally held or supported by the lugs 2 and 3 on the grate supporting means, the lugs 2 engaging in the semi-circular recesses 4 of the spider 5, and the lugs 3 engaging in the semi-circular recesses 6 which are formed in the supporting ring 7. The supporting ring 7 is held in the ordinary manner above the ash pit of the furnace 55 and the supporting arms 8 of the spider 5

are adapted to engage the ring 7 to hold the spider 5 in place. The arms 8 project upwardly from their point of engagement with the ring 7 so as to elevate the central or body portion 9 of the spider above the supporting 60 ring 7. The recesses 4 are formed in the body portion 9, so that when the grate bars 1 are in position with the lugs 2 engaging in the recesses 4, and the lugs 3 engaging in the recesses 6, the grate bars 1 will be held 65 in a sloping position, with their inner ends elevated above their outer extremities, thus giving a conical shape to the grate A.

The grate bars 1 are formed with suitable supporting fingers 10 which are spaced 70 apart to give the desired draft openings to the grate A, the supporting fingers 10 decreasing in length from the outer to the inner ends of the grate bars, the fingers projecting from the body or longitudinally extending body portion 11 of the grate bars.

Each of the grate bars 1 has a gear tooth 12 formed with and projecting from the lug 2 which is adapted to engage or mesh with the teeth 13 of the mushroom gear 14, and 80 a depending shaft 15 which is rigidly connected to the gear 14 extends through the axial opening 16 in the spider 5 and is rigidly connected on its lower end to the operating lever 17. The free 85 end of the lever 17 is pivotally connected to the operating or reach rod 18 at 19. The outer end 20 of the reach rod 18 is connected, in a suitable manner, to the shaker arm or lever which is positioned outside of the furnace, the shaker arm being of ordinary well-known construction, and not being illustrated in the drawing.

In operation of the grate A, when the reach rod 18 is operated or reciprocated back and forth by the shaker arm, the gear 14 will be turned, thus causing the grate bars 1 to turn on their pivotal lugs 2 and 3 to oscillate all of the grate bars simultaneously, or to rotate them far enough to dump the ashes 100 or fire from the grate when it is desired. In this manner the grate A is easily and effectively operated, and the conical or pyramidal shape of the grate causes the fire or fuel on the grate to assume the same shape, and thus has a tendency to evenly distribute the fuel or fire on the grate A to give the best results.

The drawing illustrates the grate A of a circular shape, but it is obvious that other shapes and forms can be used without de- 110

parting from the spirit of my invention, and the series of grate bars can be varied in number and shape as may be desired. In the construction illustrated, the grate bars 1 can be easily removed and new grate bars inserted. The even operation or oscillation of all of the grate bars simultaneously is an important feature, and allows the fire on the grate A to be effectively shaken in a very

10 easy manner.

In accordance with the patent statutes, I have described the principles of operation of my invention, together with the apparatus which I now consider to represent the best 15 embodiment thereof, but I desire to have it understood that the construction shown is only illustrative, and that the invention can be carried out by other means and applied to uses other than those above set forth within 20 in the scope of the following claims.

1. A rocking bar grate comprising a plurality of tapered grate bars provided at their ends with trunnions, fixed means for supporting said grate bars in radial arrangement, upstanding lugs formed on the inner most trunnions of said grate bars and an oscillatory head journaled in said supporting means having means adapted to engage said upstanding lugs to rock the grate bars.

25 2. A rocking bar grate comprising a fixed annular support, a hub coaxially arranged relative thereto and connected therewith, a plurality of sockets formed in said annular support, corresponding sockets formed in said hub, a plurality of grate bars having trunnions journaled in said sockets, protrusions formed on said hub trunnions, an oscillatory head mounted in said hub, means formed on said head simultaneously coating with said protrusions for simultaneously 30 rocking said grate bars and means for oscillating said head.

3. In a device of the class described, a series of triangularly shaped grate bars, ar-

ranged in radial relation, means for pivotally holding said grate bars on their inner and outer ends for oscillation about their longitudinal axes, a tooth formed on the inner end of each of said grate bars, a gear positioned above said grate bar teeth, adapted to engage said teeth and means for operating said gear to oscillate said grate bars on their pivot points.

4. In a furnace grate comprising a series of radially arranged grate bars, means for holding said grate bars pivoted at each end, an upwardly extending gear tooth, formed on the inner pivoted end of each of said grate bars, a mushroom gear for engaging said gear teeth, an operating lever connected to said mushroom gear and means connected to said operating lever which, when reciprocated back and forth, is adapted to move said mushroom gear to simultaneously oscillate said grate bars on their pivot points.

5. In a furnace grate comprising a series of grate bars, a spider for supporting the inner ends of said grate bars with their body portions extending radially of the center portion of said spider, a ring for supporting the outer ends of said grate bars, the inner ends of said bars being pivoted in said spider and the outer ends being pivoted in said ring, a series of fingers extending from the body portions of said grate bars, said fingers being spaced apart and decreasing in length from the outer ends of said grate bars toward the inner ends thereof, gear teeth formed on said segments at their inner ends, a gear axially held in said spider for engaging said teeth and means for operating said gear to oscillate said grate bars on their pivot points to shake said grate bars or to dump the same substantially as required.

ROBERT E. STURMAN.
